CLAIM

The ornamental design for a pet toy, as shown and described.

DESCRIPTION

FIG. 1 is a perspective view of a pet toy showing my new design;

FIG. 2 is a second perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an exploded view thereof;

FIG. 10 is another exploded view thereof;

FIG. 11 is a third perspective view thereof, showing the pet toy in a state of use;

FIG. 12 is a fourth perspective view thereof, showing the pet toy in a state of use; and,

FIG. 13 is an enlarged view of area '13' in FIG. 12.

The dashed broken lines depict portions of the pet toy that form no part of the claimed design. The dot-dash broken lines define the bounds of enlarged views and form no part of the claimed design.
